UNITED STATES PATENT OFFICE.

LOUIS GOTTSCHALL, OF NEW YORK, N. Y.

SIGN.

1,099,035.

Specification of Letters Patent. Patented June 2, 1914.

Application filed April 17, 1913. Serial No. 761,721.

To all whom it may concern:

Be it known that I, LOUIS GOTTSCHALL, a citizen of the United States, and a resident of the city of New York, borough of the Bronx, in the county and State of New York, have invented a new and Improved Sign, of which the following is a full, clear, and exact description.

The object of the invention is to provide a new and improved sign more especially designed for use on automobiles and the like to display a license number or other distinguishing marks which can be distinctly read, which are visible at night for a great distance, and which greatly aid the eye of an observer in detecting the number or distinguishing marks as well as aiding the memory in remembering the same.

A further object of the invention is to provide a practically unlimited number of distinct signs without unduly increasing the length of the sign or using more than five digits in the license number.

For the purpose mentioned use is made of a sign of dihedral shape and comprising two plates standing at an acute angle one relatively to the other, one of the said plates being provided with stenciled characters and a source of light at the opening formed between the spaced ends of the said plates. Use is also made of colored bands associated with the stenciled characters on the plates to provide a practically unlimited number of variations in the sign matter.

A practical embodiment of the invention is represented in the accompanying drawings forming a part of this specification, in which similar characters of reference indicate corresponding parts in all the views.

Figure 1 is a face view of the sign as applied to the rear end of an automobile to display a State license number; Fig. 2 is an enlarged sectional plan view of the same; Fig. 2^a is a perspective view of one of the sign-supporting brackets; Fig. 3 is a face view of the reflecting plate of the sign; Fig. 4 is a perspective view of a modified form of the sign; Fig. 5 is a face view of another modified view of the sign; Fig. 6 is a face view of a portion of the sign showing another modified form; and Fig. 7 is a face view of another modified form of the sign.

The light from the rear automobile lamp shining on a sign of the construction now generally used is not very effective as most

of the rays of light are dissipated. As the sign is placed back of the lamp the latter cuts off the view of a part of the number when it is situated between the observer and the sign. When the digits of the number are all rendered in the same color it is not difficult to catch and retain in one's memory consisting of not more than three digits even should the automobile be moving rapidly, but the difficulty increases with each additional digit in the license number as the monotony of the color confuses the eye of the observer and gives it no resting place or suggestion of a place at which the large number could be broken up into smaller parts. Furthermore, while the eye catches a small number, which it can cover with one glance, it can also note at the same time one or more elementary and easily distinguishable colors placed next to the number independently of the form within which these colors are confined.

The sign illustrated in Figs. 1, 2, 2^a and 3 is provided with a plate A disposed vertically and supported by horizontally-extending brackets B and B' attached to the rear of the automobile C, as plainly indicated in the drawings. In conjunction with the plate A operates a second plate D connected at the right-hand end by hinges E with the corresponding end of the plate A so that the plate D is adapted to extend at an acute angle relatively to the plate A, but may be folded upon the back of the latter, as indicated in dotted lines in Fig. 2. The plate D is held locked in open position by a bolt B² engaging the plate D and a lug B³ on the bracket B. When the bolt B² is removed the plate D can be swung into a closed position and locked therein by the front bolt B⁴ and by spring catches D' on the lower edge of the plate D engaging the lower edge of the plate A. A source of light F in the form of a lamp is arranged at the opening or space between the spaced ends of the plates A and D, and this source of light F is supported on a suitable bracket G attached to the automobile C. The plate A is provided with perforations H representing indicating characters, such as numerals, letters, symbols, geometrical figures and the like, to indicate a license number as hereinafter more fully explained. The inner face of the plate A is coated with a reflecting surface, such as white enamel or the

like, and a similar coating may be arranged on the opposite face of the plate D whereby the rays of light emanating from the source of light F and passing to the reflecting surfaces of the plates A and D and then being again reflected from each of these surfaces to the other cause a vivid illumination of the indicating characters H so that the same can be readily distinguished even at the time 5 the automobile is quite a distance away from the observer. It will be understood that as the plates A and D are arranged at an acute angle one relatively to the other, and the source of light is located at the opening between the spaced ends of the said plate, it is evident that the portion remote from the source of light, that is, the portion nearer the hinges E is strongly illuminated owing to the smaller distance the reflected rays of 10 light have to travel between the reflecting surfaces of the plates A and D. During the day the source of light F is not used, and then the plate D is swung into closed position and locked therein, as indicated in dotted lines in Fig. 2, so as to overlie the inner face of the plate A whereby the reflecting inner surface of the plate D is at the perforations H to cause the same to appear vividly to the observer. Also since the plate 15 A is in front of the lamp F the latter will not obstruct the view of any part of the number either in the daytime or at night. If a number on the plate A consists of more than three digits, the additional digit to the left of the third digit expressing the thousands may be distinguished from the other digits by a colored band I on the inner surface of the plate D directly in the back of the said digits thus relieving the eye from 20 the confusion caused by the monotony of color and at the same time suggesting the natural breaking up of the number into two smaller parts (the one consisting of the thousands and the other of the units) which 25 can be caught by the eye and retained by the memory more easily than the succession of four or five digits all of the same color. As shown in Fig. 1, the license number is 11571, of which the two digits to the left appear 30 green owing to the colored band I being of this color and appearing behind the two left digits "11." Owing to the angle between the plates A and D the colored band I is wider than the space occupied by the digits 35 expressing the thousands, so that these digits appear colored even if the sign is viewed somewhat from the side instead of immediately in the rear of the sign. By placing the colored band I in back of the last two digits of each number (see Fig. 4) instead of the first two, a new additional series of the same number of signs is obtained, each of the signs being distinguished from the corresponding sign of the first series by the 40 location of the colored band on the back 45

plate D. If the color of the band I is, for instance, green and it is designated by its initial letter "G" the license number of the sign shown in Fig. 1 may be expressed G11571, while that illustrated in Fig. 4 may be expressed 09165G, that is, when the color band is green on the left-hand side the letter "G" is placed at the beginning of the number, and when the colored band is at the right-hand side it is placed at the end of the license number. In either of the cases mentioned that part of the front face of the plate A which is directly in front of the colored band I is rendered white (see Figs. 1 and 4) to provide the necessary contrast in the daytime, while the remaining part of the front face of the plate A is colored with a color adopted by each State and which color also provides the necessary contrast for the white figures. By the arrangement described, the highest number to be stenciled on the plate A is reduced to one-half the number of the signs desired. For instance, in the State of New York the number of automobiles is at present about 140,000, which is a number consisting of six digits, but with the arrangement described the highest number to be stenciled will be 70,000, of five digits only. The avoidance of a sixth digit is accomplished in the State 90 of New York by the use of letters of the alphabet as additional identification marks, but said additional marks must be remembered by the observer out of the twenty-six letters of the alphabet. By repeating the 95 same numbers with stripes I of different colors a practically unlimited number of signs can be obtained.

In the modified form shown in Figs. 5, 6 and 7 numbers of not more than three digits 105 are employed, and instead of one colored band I two colors are used disposed within a square or any other regular diametrical figure, the latter being divided into four quadrants which are preferably designated by the numbers 1, 2, 3, 4, as follows: Two 110 easily distinguishable elementary colors are preferably chosen, such as orange and green. By rendering only one of the four quadrants in one of the two colors mentioned 115

$$4 \times 2 = 8$$

variations are obtained. There are six different ways in which the four quadrants may be combined in pairs, namely: 1, 2; 120 4, 3; 1, 4; 1, 3; 2, 4. There are also four different ways of applying the two colors to any of the six pairs, namely: both may be colored with one color or both with the other color, or one with one color and the other with the other color or vice versa, so as to obtain 125

$$6 \times 4 = 24$$

variations. Thus including the case when 130

none of the four quadrants are colored, there are altogether

$$8+24+1=33$$

5 variations. By introducing "0's" at the beginning of the numbers giving rise to number of the form 07; 006; 098; etc., it is possible to provide 1110 numbers, each of not more than three digits. By using the 10 color scheme above described either to the right or to the left of each of these numbers, it is possible to obtain

$$2 \times 3 \times 1110 = 73,260$$

15 distinct license numbers. By using the initials of the colors in conjunction with the color scheme, as previously mentioned, the license numbers can be expressed as follows: O₁G₃123; 123G₄; 346G₁O₃; 540₂O₄; etc., according to the colors and their spaces in the square. It is understood that the colors are placed on the back plate D directly in back of the square H' perforated or stenciled in the front plate A, as shown in Figs. 5 and 7. 25 In case a State needs more than 73,260 signs, then three colors may be chosen, for instance, orange, green and red, and by coloring not more than two quadrants as before with either one or two out of the three 30 chosen colors it is possible to obtain

$$2(4 \times 3 + 6 \times 9 + 1) \times 1110 = 148,740$$

distinct signs. If a larger number is needed another color is added but not more than 35 two colors appear on the plate. It is evident that by means of this simple device an unlimited number of signs can be obtained, on none of which more than three digits appear, which can be seen at a glance and 40 taking in at the same time one or two colors in the square, as the eye is not burdened with observing the form within which these colors are confined, the form remaining always the same, that is, a quadrant of the 45 regular figure. For smaller States the figures may be simplified. In the State of Connecticut, for instance, there are at present 17,000 automobiles, and the signs for this State may be provided with half of a 50 square in conjunction with two colors only, giving rise to

$$18 \times 1110 = 19,980$$

variations in the signs.

55 The length of the sign can always remain the same no matter how large the number of signs desired, for with the increase of the number of signs all that it is necessary to do is to increase the number of colors from

which the two colors in question are chosen, 60 but as these two colors are always confined within the figure chosen and the number of digits does not exceed three, the lengths of the signs remain constant.

Having thus described my invention, I 65 claim as new and desire to secure by Letters Patent:

1. A sign, comprising two plates, one movable relative to the other, the plates in one position standing at an acute angle one 70 relative to the other, and the plates in another position overlying one the other, one of the said plates being provided with perforations representing sign matter and both plates in either of the said positions forming 75 active members of the sign, and a source of light so positioned as to be at the opening formed by the spaced ends of the said plates at the time the latter are standing at an angle one relative to the other, and so positioned as to illuminate the opposed faces of the said plates.

2. A sign, comprising two plates, one movable relative to the other, the plates in one position standing at an acute angle one 85 relative to the other, and the plates in another position overlying one the other, one of the said plates being provided with perforations representing sign matter and the other plate being provided at its inner face 90 with a colored space opposite sundry of the said perforations, and a source of light so positioned as to be at the opening formed by the spaced ends of the said plates at the time the latter are standing at an angle one relative to the other.

3. A sign, comprising a front plate and a rear plate, the plates being movable one relative to the other, and the plates in one position standing at an acute angle one 100 relative to the other, and the plates in another position overlying one the other, the front plate having spaced perforations, and the said rear plate having a colored space opposite sundry of the said perforations, a 105 source of light so positioned as to be at the opening formed by the spaced ends of the said plates at the time the latter are in open position, and means to hold the said plates in either of the said open or closed positions. 110

In testimony whereof I have signed my name to this specification in the presence of two subscribing witnesses.

LOUIS GOTTSCHALL.
